(57) **CLAIM**

The ornamental design for a stroller cart frame with storage baskets, as shown and described.

DESCRIPTION

FIG. 1 is a left side elevation view of a stroller cart frame with storage baskets showing my new design;

FIG. 2 is front elevation view of the stroller cart frame with storage baskets;

FIG. 3 is a right side elevation view of the stroller cart frame with storage baskets;

FIG. 4 is a rear elevation view of the stroller cart frame with storage baskets;

FIG. 5 is a top plan view of the stroller cart frame with storage baskets;

FIG. 6 is a bottom plan view of the stroller cart frame with storage baskets;

FIG. 7 is a perspective view of the stroller cart frame with storage baskets taken from a top, rear and right side perspective; and,

FIG. 8 is a perspective view of the stroller cart frame with storage baskets taken from a top, front and left side perspective.

Broken-lines showing other elements of a stroller cart, which elements include a foldable child seat, a knob on a push handle, a lower tray and casters, are for illustrative purposes only and form no part of the claimed design.
